UNITED STATES PATENT OFFICE.

GUSTAV HOFFMAN, OF CHICAGO, ILLINOIS.

TYPE-HOLDER.

1,343,917.

Specification of Letters Patent. Patented June 22, 1920.

Application filed November 24, 1919. Serial No. 340,191.

To all whom it may concern:

Be it known that I, GUSTAV HOFFMAN, a citizen of the United States, and a resident of the city of Chicago, county of Cook, 5 and State of Illinois, have invented certain new and useful Improvements in Type-Holders, of which the following is a specification.

My invention relates to new and useful 10 improvements in type holders, and more especially to such holders employed as marking dies, the object of the invention being to provide a simple and efficient device of this character which will properly hold the 15 type during use and permit of the ready removal thereof, when it is desired to change the marking type.

Other objects will appear hereinafter.

The invention consists in the combinations and arrangements of parts hereinafter 20 described and claimed.

The invention will be best understood by reference to the accompanying drawings forming a part of this specification, and in 25 which,

Figure 1 is a side view, showing parts in section of the type holder embodying the invention,

Fig. 2 is a partial transverse section of 30 the same,

Fig. 3 is an end view of the same, and

Fig. 4 is a detailed view of one of the type bodies employed in the construction.

The preferred form of construction as 35 illustrated in the drawings, comprises a suitable body or handle 5, having a type receiving socket 6 in one end thereof adapted to receive the type 7, as indicated, with the operative faces of the type protruding from the body, as shown. Each of 40 the type bars or blocks 7 is provided on one side with a semi-cylindrical notch 7' and a bore is extended through one side of the socket 6, said bore being enlarged 45 at its opposite ends to form receiving recesses 8 and 9. A locking pin 10 is longitudinally insertible in said bore so as to fit within the notches 7' of the type bar 7 to lock said type bars in place. The pin 50 10 is provided at one end with a head 11, fitting within the recess 8, as indicated, and the other end of the pin protrudes slightly into the recess 9, as shown. A spring-held latch 12 is slidably mounted in

55 the body 5 in a substantially U-shaped recess 13 therein. The latch 12 is substantially

U-shaped in form, one limb 14 thereof being arranged and adapted to project into the recess 8 across the outer side of the head 11 of the pin 10, when said pin is in locking 60 position. The other limb 15 of the latch 12 carries a push-button 16 projecting from the face of the holder 5, and a compression spring 17 normally holds the latch 12 in engagement with the head 11 of pin 10. 65 By this arrangement, it will be observed that the type bar will be securely and solidly held locked in the type socket 6 during the use thereof. When it is desired to remove the type, the button 16 is depressed with 70 the thumb, thus releasing the pin 10, which may then be removed, thus releasing the type 7. Should the pin 10 stick in its bore for any cause, the same may be readily removed by striking the end thereof in the 75 recess 9, which thus protects the protruding end of the pin, and gives access thereto. The specific form and arrangement of parts is a simple and effective one for the purpose.

While I have illustrated and described 80 the preferred form of construction for carrying my invention into effect, this is capable of variation and modification without departing from the spirit of the invention. I, therefore, do not wish to be limited 85 to the precise details of the construction set forth, but desire to avail myself of such variations and modifications as come within the scope of the appended claims.

Having described my invention, what I 90 claim as new and desire to secure by Letters Patent is:

1. A type holder comprising a body, having a type receiving socket therein and a bore traversing one side of said socket; a 95 locking pin longitudinally insertible in and removable from said bore; type insertible in said socket and notched to engage said pin; and a spring-held latch engaging said pin to prevent removal thereof, substantially 100 as described.

2. A type holder comprising a body, having a type receiving socket therein and a bore traversing one side of said socket; a locking pin longitudinally insertible in and removable from said bore, the head of said pin engaging one side of said body; type insertible in said socket and notched to engage said pin; and a spring-held latch engaging across the head of said pin to prevent the removal thereof, substantially 110 as described.

3. A type holder comprising a body, having a type receiving socket therein and a bore traversing one side of said socket, one side of said bore being enlarged into a receiving recess; a locking pin longitudinally insertible in and removable from said bore, the head of said pin fitting into said recess; type insertible in said socket and notched to engage said pin; and a spring-held latch engaging across the head of said pin to prevent the removal thereof, substantially as described.
4. A type holder comprising a body, having a type receiving socket therein and a bore traversing one side of said socket, one side of said bore being enlarged into a receiving recess; a locking pin longitudinally insertible in and removable from said bore, the head of said pin fitting into said recess; type insertible in said socket and notched to engage said pin; a spring-held latch engaging across the head of said pin to prevent the removal thereof; and a depressible pin for releasing said latch, substantially as described.

5. A type holder comprising a body, having a type receiving socket therein and a bore traversing one side of said socket, both ends of said bore being enlarged into receiving recesses; a locking pin longitudinally insertible in and removable from said bore; a head on said pin fitting into one of said receiving recesses; type insertible in said socket and notched to engage said pin; and a spring-held latch slidably mounted in said body, said latch being in substantially U-form, one limb of said latch projecting across the head of said pin and the other limb of said latch being provided with a button projecting from the side of said body whereby the depression of said button releases said pin, substantially as described.

In testimony whereof I have signed my name to this specification in the presence of two subscribing witnesses.

GUSTAV HOFFMAN.
